2 SHEETS-SHEET 2

UNITED STATES PATENT OFFICE.

CLIFFORD S. GOBY, OF CLEVELAND, OHIO.

INTERNAL-COMBUSTION ENGINE.

Application filed December 26, 1916. Serial No. 138,703.

To all whom it may concern:

Be it known that I, CLIFFORD S. GOBY, a citizen of the United States, residing at Cleveland, in the county of Cuyahoga and State of Ohio, have invented a certain new and useful Improvement in Internal-Combustion Engines, of which the following is a full, clear, and exact description.

This invention relates to improvements in internal combustion engines and has for its object to provide an engine preferably of the rotary valve type which is efficient, silent and otherwise satisfactory in operation, compact, durable, easily machined and assembled.

A still further object is to so arrange a rotary valve in the engine and to so construct and assemble the parts which are associated with the valve and constituting the casing or chamber therefor, that the valve will run smoothly and with little friction, is effectively cooled and is not subjected to the intense heat of combustion, and is not affected by expansion or contraction due to temperature changes.

More particularly, the invention aims to provide an engine having a cylinder liner with an integral head forming the combustion chamber and adapted to be inserted in the main engine casting or housing which may be of aluminum, so as to form between the latter and the head of the liner an annular space for the rotary valve. An additional specific object is to arrange for cooling both the inner and outer walls of the chamber or annular space which receives the valve, and to support the valve at its upper and lower ends on tapered surfaces while the cylindrical portions of the valve proper run practically without contact with either the inner or outer wall of the chamber, the valve being thus centered, and the tapered bearing surfaces as well as other elements embodied in or associated with the valve forming an effective seal against leakage either longitudinally or circumferentially of the valve.

The above and other objects, advantages and desirable features are attained by my invention which may be briefly summarized as consisting in certain novel details of construction and combinations and arrangements of parts which will be described in the specification and set forth in the appended claims.

In the accompanying sheet of drawings wherein I have shown the preferred embodiment of my invention, Fig. 1 is a vertical longitudinal sectional view through one cylinder of the engine; Fig. 2 is a top plan view of the four-cylinder engine embodying my invention, parts being in section and parts being removed to show the construction of the valves, their arrangement in the heads of the cylinders, the manner in which they are cooled and the actuating mechanism therefor; Fig. 3 is a partial sectional view on an enlarged scale showing particularly the details of the valve and of the parts immediately surrounding the same; Fig. 4 is a horizontal sectional view through the head of the cylinder liner; Fig. 5 is a side elevation of the cylinder liner removed from the aluminum body or housing designed to receive it; Fig. 6 is a side view of the valve removed from the engine, portions being broken away; Fig. 7 is a detailed sectional view substantially along the line 7-7 of Fig. 6; and Fig. 8 is a plan view of the two valve sectors removed.

Referring now to the drawings, 10 represents the body or housing of the engine which can be designed to contain one or any desired number of cylinders. In Fig. 2 I have shown a housing adapted for four cylinders, this housing being preferably an en bloc casting of aluminum. Into each cylinder chamber of the housing 10 there is inserted a cast iron liner 11, which is pressed down into the housing until a flange 12 of the liner seats on a shoulder 13 of the housing. The liner is then secured in position by a ring or nut 14 which is screwed onto the lower part of the liner until it abuts the lower end of the housing, as shown in Fig. 1.

The liner is provided with an integral head having an inner truncated conical wall 15 which forms the combustion chamber 16, and in the upper end of which is screwed a bushing 17 which receives the spark plug 17^a. The head is provided also with an outer cylindrical wall 18 which forms the inner wall of the valve chamber. Between the walls 15 and 18 there is a water jacketing space 19 and bridging this space and extending from the inner combustion chamber outwardly through the wall 18, are admission and exhaust passageways 20 and 21 which as here shown are arranged at an angle of about 125° with respect to each other.

The housing 10 extends upwardly around the cylinder head just referred to, the portion above the flange 12 being spaced from the cylinder head and forming the outer wall 5 of the valve chamber. The housing is provided with a water jacketing space 22 which extends up substantially to the top of the housing, and extending through the housing across this space is a gas inlet passageway 10 23 and an outlet or exhaust passageway 24 which extend toward or register with the inlet and exhaust passageways 20 and 21 in the head of the cylinder liner and are adapted to be placed in communication 15 therewith by the rotary valve to be described presently. As will be apparent from Fig. 2, the housing has one inlet passageway 23 for each pair of cylinders as each passageway 23 communicates with the inlet passageways in 20 heads of two adjoining cylinders while the housing has a separate exhaust passageway 24 for each cylinder. It will be understood that the passageways 23 and 24 will be connected respectively with inlet and exhaust 25 manifolds.

In the annular space between the wall 18 of each cylinder head and the outer surrounding wall of the housing is a rotary cylindrical valve which controls the admission 30 to and exhaust of gases from the cylinder, the valve having in its side walls two oppositely disposed ports 25, 25, which successively place the inlet and exhaust passageways 23 and 24 of the housing in communication 35 with the combustion chamber of the cylinder head, the valve being rotated at such a speed that admission and exhaust take place at just the desired instants and in properly timed relationship with respect to 40 the movements of the piston which is shown at 26 in Fig. 1.

The valve includes a cylindrical shell in the form of a valve body 27 and a packing which in many respects is similar to that 45 constituting the subject matter of my prior application Serial No. 47,953, filed August 30, 1915, patented July 24, 1917, No. 1,234,460. The valve body 27 while adapted to rotate between the inner and outer cylindrical surfaces of the liner head and housing, 50 does not engage said cylindrical surfaces but is supported on and centered by two tapered surfaces at the top and bottom of the valve, one being shown at 28 and being the top of 55 the flange 12 previously referred to, and the other being shown at 29 and located at the upper outer part of the liner head. It will be seen from Fig. 3 that between the cylinder head and the valve body is an annular clearance space. The tapered step bearing surfaces 60 centralize or keep the valve concentric with respect to the axis of the cylinder, and they hold the valve in a position such that the clearance space just referred to may be 65 maintained between the cylinder-head and

valve without liability of lateral movement between the valve and the cylinder-head. In the claims I do not limit myself to two of these tapered step bearings for practice has shown that very good results can be obtained with a single tapered step bearing, particularly when arranged at the top of the valve, so as to support the weight of the valve at the same time that it centralizes it. 70

The packing which surrounds the valve 75 body includes two sectors 30, each extending about half-way around the valve body, said sectors being pressed yieldingly outward against a liner 31 in the upper part of the housing, by split spring rings 32 between 80 the sectors and the valve body. These sectors are held against rotary movement relative to the valve body by lugs or other abutments 33 (see particularly Fig. 7), although they may otherwise move relative to the 85 valve body due to expansion or contraction or by any inequalities in the valve chamber, it being observed from Fig. 3 that there is normally a slight clearance space between the inner surfaces of the sectors and the 90 valve body. These sectors or sector plates are provided with port openings which register with port openings formed in the valve body to form the ports 25, 25, previously referred to, and they are provided also with 95 longitudinally extending grooves 34 which prevent leakage of gas circumferentially and distribute the lubricant evenly over the surfaces of the valve. The grooves also render the sectors more flexible in action. 100

For the purpose of preventing leakage of gas longitudinally of the valve, the valve body is provided above and below the sectors with split spring rings 35 which engage the inner surface of the valve chamber 105 liner 31. Additionally the upper part of the cylinder liner head is provided with grooves in which are seated split spring rings 36. These rings together with the tapered bearing surfaces form a very effective seal against leakage longitudinally of the valve. The packing rings 35 and 36 preferably consist of spring channel shaped rings containing a suitable composition packing, such as asbestos soaked in graphite. 110 115

The valve for each cylinder is provided at its upper end with a driving gear 37, the gear being preferably formed by cutting the teeth directly in the enlarged upper end of the valve body. Each gear meshes with 120 the gear of the adjoining valve forming a train which is driven by a pinion 38 which engages one of the larger gears and is secured to the upper end of a vertical shaft which extends downwardly and will be 125 driven by suitable mechanism from the crank shaft.

The upper part of the engine including the gearing just referred to, is closed by a cap 40 which preferably extends the length 130

of the aluminum engine housing and is securely bolted both to the housing and to the several heads of the cylinder liners. It will be observed that this cap is provided with 5 a water jacketing space 41 which communicates with the water jacketing space 19 in the head of each cylinder liner as shown in Fig. 3 and communicates also with the jacketing space 22 in the housing through 10 triangular shaped openings 22^a shown in Fig. 2. It may be stated at this point that there will be a good circulation of cooling medium through the upper part of the motor where the greatest heat is encountered, the circulation taking place through 15 the housing surrounding the cylinders and liner heads, and also through the individual liner heads and upper cap 40. In addition to the water jacketing space 41 the cap 40 is provided with longitudinally extending 20 lubricant passageways 42 which communicate with the several annular valve chambers so as to lubricate the gears and the bearing surfaces of the valves.

25 The cylinder liner construction as herein described has numerous advantages over the usual constructions as it permits any number of cylinders to be arranged en bloc giving extreme rigidity, characteristic of 30 the all block casting designs, but without the numerous disadvantages of the cast block design wherein the cylinders are cast integral with the valve body. Heretofore the tendency has been to make the cylinder 35 head detachable, this being done to facilitate machining and to permit the best arrangement of poppet valves. However, the detachable head requires the use of copper-asbestos gaskets which must be fitted with 40 great care to prevent leakage under the severe internal pressure during ignition. With the rotary valve in the present construction arranged as herein shown and described, the head can be cast integral with 45 the liner and in consequence there is no possible danger of leakage where leakage with the detachable heads has been prevalent.

50 It will be observed also, that substantially ideal cooling conditions are obtained. The head end of the engine carries an ample supply of water which effectively cools the parts where maximum heat is encountered, including the walls about which the valves 55 revolve, the water jacketing space being so arranged that the valve body and the packing are maintained at a suitably low temperature. Not only is the valve very well cooled, but it will be observed that it is 60 not subjected to the direct flame during explosion or combustion, and in fact the construction is such that the valve will run smoothly and very little power will be required to operate it under the most strenuous 65 conditions.

Additionally the short, straight, carefully designed passageways leading to and from the cylinder, and the amply large port areas are conducive to a maximum volumetric capacity and efficiency.

70 The valve itself is extremely simple, there being an absence of numerous small parts, the valve and its packing being designed not only for simplicity of construction and efficiency of operation, but ease of 75 manufacture. The valve cannot stick or become seriously injured due to extreme heat or lack of lubrication, especially because the packing automatically accommodates itself to any conditions of expansion and contraction, and it also automatically compensates 80 for irregularities in the walls of the chamber, or to variations in diameter due to wear.

85 While I have shown the preferred construction, I do not wish to be confined to the same as changes in details of construction or arrangement may occur to one skilled in the art, and I therefore aim in my claims to cover all modifications which 90 do not involve a departure from the spirit and scope of my invention.

Having thus described my invention, what I claim is:

1. In an internal combustion engine, a 95 cylinder having at one end thereof, inner and outer cylindrical walls forming a valve chamber whose axis is coincident with the axis of the cylinder, a rotary open topped cylindrical valve in said chamber provided 100 with an offset tapered end portion, and a tapered step bearing surface carried by one of the walls of the valve chamber, and engaged by the tapered end portion of the valve.

105 2. In an internal combustion engine, a cylinder having at the head thereof inner and outer spaced walls forming an annular chamber whose axis is coincident with the axis of the cylinder, said chamber having 110 at the ends thereof tapered surfaces forming step bearings, and a rotary valve in said chamber and seated on said tapered surfaces.

115 3. In an internal combustion engine, a cylinder having at the head thereof inner and outer spaced walls forming an annular chamber whose axis is coincident with the axis of the cylinder, said chamber having 120 at the ends thereof tapered surfaces forming step bearings, a rotary valve in said chamber and seated on said tapered surfaces, said valve having a packing for preventing leakage of gas.

125 4. In an internal combustion engine, a housing, a cylinder liner seated in the housing and having a head, the head being spaced from the surrounding portion of the housing forming an annular chamber whose axis is coincident with the axis of the cyl- 130

inder, the head being provided, near the top and bottom of the chamber, with tapered surfaces, and a rotary cylindrical valve in said chamber and resting on said surfaces.

5. In an internal combustion engine, a housing, a cylinder liner seated in the housing and having a head, the head being spaced from the surrounding portion of the 10 housing forming an annular chamber whose axis is coincident with the axis of the cylinder, the head being provided, near the top and bottom of the chamber, with tapered surfaces, and a rotary cylindrical 15 valve in said chamber and resting on said surfaces, and a gear at the end of the valve for rotating the same.

6. In an internal combustion engine, a 20 housing, a cylinder liner seated in the housing and having a head, the head being spaced from the surrounding portion of the housing forming an annular chamber whose axis is coincident with the axis of the cylinder, the head being provided, near the 25 top and bottom of the chamber, with tapered surfaces, and a rotary cylindrical valve in said chamber and resting on said surfaces, said valve comprising a valve body and packing surrounding the same for preventing leakage of gases.

7. In an internal combustion engine, a 30 cast metal housing having a cylinder opening and an internal shoulder between and at a distance from both ends of said opening, a cylinder liner seated in said opening and having between its ends an external flange resting on said shoulder, and means for securing the liner and housing together.

8. An internal combustion engine having 40 a housing with a cylinder opening, the upper portion of which is of larger diameter than the lower portion and there being an internal shoulder between said portions; a cylinder liner seated in the housing and

having an external shoulder engaging the 45 internal shoulder of the housing, said liner having a head projecting up into the portion of the opening of the housing of the larger diameter.

9. An internal combustion engine having 50 a housing with a cylinder opening, the upper portion of which is of larger diameter than the lower portion forming a shoulder, a cylinder liner seated in the cylinder opening of the housing, the portion of said liner 55 projecting above said shoulder of the housing forming with the surrounding wall of the housing a valve chamber, said liner having between its ends a flange resting on said shoulder of the housing and forming 60 the base of the valve chamber.

10. An internal combustion engine having 65 a housing with a cylinder opening, the upper portion of which is of larger diameter than the lower portion forming a shoulder, 70 a cylinder liner seated in the cylinder opening of the housing, the portion of said liner projecting above said shoulder of the housing forming with the surrounding wall of the housing a valve chamber, said liner having between its ends a flange engaging said shoulder of the housing and forming the base of the valve chamber, the upper surface of said flange being tapered.

11. In an internal combustion engine, a 75 cylinder having at the outer end thereof inner and outer cylindrical walls forming an annular valve chamber whose axis is coincident with the axis of the cylinder, said chamber having at its upper end a tapered 80 step bearing, and a rotary valve in the chamber in the form of an open ended cylinder, said valve being provided adjacent its upper end with an offset tapered portion resting on said tapered step bearing.

In testimony whereof, I hereunto affix my signature.

CLIFFORD S. GOBY.
